CLAIM

The ornamental design for a toy ball, as shown and described.

DESCRIPTION

FIG. 1 is a front elevation view of a toy ball showing my new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a perspective view thereof; and,

FIG. 8 is a fragmentary cross section view thereof taken on line 8—8 of FIG. 7.

The broken lines shown in the drawings indicate environmental structure which form no part of the claimed design.

1 Claim, 8 Drawing Sheets
